UNITED STATES PATENT OFFICE.

WILLIAM A. RINGLER, OF PHILADELPHIA, PENNSYLVANIA, ASSIGNOR TO THE
GLOBE-WERNICKE CO., A CORPORATION OF OHIO.

VISIBLE INDEX.

Application filed November 19, 1924. Serial No. 750,745.

This invention relates to visible index devices, and particularly to the type in which a series of index elements or units are supported for sliding movement in a frame, with the free edges of the units or elements projecting one beyond the other in a progressively overlapping manner, whereby each element will have an exposed marginal edge adapted to carry identification characters which will always be visible. This invention more particularly relates to the mounting of the index elements or sheets for sliding movement in the frame, and is in the nature of an improvement upon the carrier for index elements disclosed and claimed in my prior United States Patent #1,503,559, issued August 5th, 1924.

An object of the invention is to provide an improved carrier for index elements which may be made partially or entirely of sheet metal; and which will be light in weight, rigid, durable, convenient, and relatively inexpensive.

A further object is to provide an improved carrier for index elements, to which the elements may be attached or detached therefrom easily and rapidly, and in a simple manner; and to which the elements will be effectively secured when attached thereto.

A further object is to provide an improved carrier for index elements upon which the element may be slidingly mounted, and with which sliding movement of the elements thereon will be limited in a simple manner.

Various other objects and advantages will be apparent from the following description of an embodiment of the invention, and the novel features will be particularly referred to hereinafter in connection with the appended claims.

In the accompanying drawings:

Fig. 1 is a perspective of a carrier constructed in accordance with this invention;

Fig. 2 is an elevation of a portion of a frame with a number of carriers supported thereby and illustrating the manner of inserting or removing the carriers;

Fig. 3 is a similar elevation on a larger scale with an index sheet attached to a carrier;

Fig. 4 is a transverse sectional elevation of the same taken substantially along the line 4-4 of Fig. 3; and

Fig. 5 is a similar sectional elevation with

the section taken substantially along the line 5-5 of Fig. 3.

In the illustrated embodiment of the invention, the index units are supported in oppositely facing guide grooves *a* provided in a frame or supporting element *b*, as usual in visible index devices. In the guide grooves *a*, the various carriers for index elements are mounted for sliding movement along the frame, being held normally together by a suitable follower block (not shown) as usual in such devices. Each index carrier in the illustrated embodiment comprises two hinged sections *c* and *d*, section *c* being guided in the grooves *a* and the section *d* mounting the index sheet or card.

The section *c* is formed of a channel-shaped strip of sheet metal, with the channel running lengthwise thereof, the length of the strip being greater than the distance between the open sides of the grooves *a* and less than the distance between the bottoms of the grooves. Adjacent each end of the channel strip, a tongue 1 is struck up from the main face thereof, leaving an aperture 2, and the tongue is rolled upwardly and backwardly upon itself to form an outwardly elongated or oval bearing loop or projection for the attachment of the other section *d*. The sections *c* are disposed in the supporting frame with the open faces of the channels down, that is, against the face of the frame, and with the main faces from which the tongues 1 are struck, facing upwardly or outwardly.

Each section *d* is also channel-shaped, with the channel running lengthwise thereof, the bottom or main face 3 of this channel being disposed flat against the bottom or outer face of the corresponding wall of the other channel section *c*. One edge or side wall of the channel of the section *d* is longer than the other edge, the bottom wall 3 being coextensive along that side wall for a short distance from that edge, so that a projecting angular tongue 5 will be formed at each end of the section. The side wall or flange 4 of each angular tongue 5 is bent over upon the extending end of the bottom wall 3, so as to form a more nearly cylindrical bearing element or tongue, which tongues are rotatably mounted in the loops or bearing projections formed by the rolled tongues 1 of the chan-

nel section *c*. The tongues 5 thus serve as hinge pintles connecting the sections *c* and *d*.

The side wall or flange 4 is provided with an angular marginal extension 6, which extends approximately parallel with the bottom face 3 and over the free edge of the other side wall or flange 7 of the same strip, the extension 6 being slightly spaced from the free edge of the flange 7 to provide a slot through which the index sheets or cards may pass. The extension 6 is shorter than the flange 4 from which it projects for a purpose which will appear presently.

The index sheets or cards 8 are provided with flanges or bent over marginal edges 9, and such marginal edges are slidingly mounted in the channels of the sections *d* as shown in Figs. 3 to 5. The width of the sheet or card is slightly less than the width of the channel of the section *d*, so that when the folded over marginal portion 9 of each index sheet or card is inserted through the space between the extension 6 and the flange 7, the bent over edge 9 may spring away from the body of the sheet and snap into the bottom of the channel of the section *d*. This marginal edge then engages with the flange 7 to prevent withdrawal of the index sheet or element by pulls thereon. The sheet may be slid laterally of itself, which will be longitudinally of the channel section *d*, in order to remove it from the channel section, and by a reverse sliding movement it may be reattached, but the attachment to a carrier is more readily accomplished by inserting the bent marginal edge 9 directly into the channel between the extension 6 and the flange 7.

The marginal edge 9 is preferably slightly shorter than the width of the index sheet or card and the corners of the index sheet or card, adjacent the marginal or bent over edge 9 are notched or beveled, as at 10, so that the sheet or card will fit between the loops or bearing eyes of section *c* as shown in Fig. 3. The loops formed by the tongues 1 will, therefore, normally prevent lateral sliding of the index sheets or cards, until the side edges of the cards or sheets have first been flexed slightly to clear them of the bearing loops or projections.

Any number of separate superposed sheets or cards 8, with their bent over or flanged edges nesting over one another, may be inserted into any channel section *d* so as to provide a plurality of leaves to each index element or unit, or multi-leaf sheets or cards may have their folded over edges inserted in the carriers in the same manner. With this arrangement it will be observed that any index sheet or card may be removed from or applied to its carrier without removing the latter from the frame. The carrier being rigid against flexure in a transverse direction, it may be inserted into or removed

from the guide grooves *a* by first moving it into a somewhat oblique or diagonal position, as shown in dotted lines in Fig. 2, so that the ends will be clear of the guide grooves.

It will be obvious that various changes in the details and materials, which have been herein described and illustrated in order to explain the nature of the invention, may be made by those skilled in the art within the principle and scope of the appended claims.

I claim:

1. In a visible index device, an elongated member of sheet metal having transversely extending tongues cut therefrom and bent to form bearing loops upon a face of the member, a single holder having tongues rotatable in said loops and also having portions for the attachment of index sheets thereto, whereby the sheets will be hingedly connected to the said member.

2. In a visible index device, an elongated member of sheet metal, relatively rigid against flexure in a transverse direction; having transversely extending tongues cut therefrom and bent to form bearing loops, and a holder having extensions from opposite ends hinged in said loops and also having portions for the attachment of index sheets thereto, whereby the sheets will be hingedly connected to said member.

3. In a visible index device, a channel-shaped strip of metal having transversely extending tongues struck out therefrom and bent upon themselves to form bearing loops upon a face thereof, and an index element hinged in said loops.

4. In a visible index device, an elongated member of sheet metal having transversely extending tongues struck from the interior of a portion thereof and bent to form bearing loops upon a face of the member, and an index element hinged in said loops.

5. In a visible index device a channel-shaped strip of sheet metal, the channel running lengthwise of the strip, said strip having tongues extending transversely thereof struck out from the interior of the bottom wall of the channel and rolled upon themselves to form projecting bearing loops, and index elements hinged in said loops.

6. In a visible index device, a channel-shaped strip of sheet metal, the channel running lengthwise of the strip, said strip having tongues extending transversely thereof struck out from the interior of the bottom wall of the channel and rolled upon themselves to form projecting bearing loops, and a sheet metal hinge member, having bearing tongues extending from the ends and rotating in said loops, said hinge member having a portion formed for the attachment of index sheets thereto, whereby the sheets will be hingedly connected to said member.

7. In a visible index device, a base strip

- having bearing loops projecting from a face thereof, a hinge member formed of sheet metal having aligned tongues extending from opposite ends adjacent an edge, 5 said tongues being rolled along lines extending lengthwise thereof to form large bearing pintles which are rotatably mounted in said loops, said hinge member having the portion intermediate the tongues formed for the 10 attachment of index sheets, whereby the latter will be hingedly connected to the member.
8. In a visible index device, a carrier for index sheets comprising two articulately connected elongated members, one of said members being shorter than the other and formed of sheet metal, said sheet metal member having a flange extending from one edge across a face thereof toward and over the 20 other edge and in spaced relation thereto, the opposite edge of said sheet metal member also having a flange extending toward the other flange solely in a direction approximately normal to the face of the first flange 25 and at approximately 90° to the plane of the sheet metal member but terminating in spaced relation to the other flange.
9. In a visible index device, a carrier for index sheets comprising two hingedly connected elongated members, one of said members being shorter than the other and formed of sheet metal, said sheet metal member having a flange extending from one edge across a face thereof and toward the other edge 35 and in spaced relation thereto, the opposite edge of said element also having a flange extending approximately normal to the face of the first flange and at approximately 90° to the plane of the sheet metal member but 40 terminating, without material deviation from its said normal direction, in spaced relation to the other flange, the overhanging flange being shorter from side to side than the other flange, whereby the flanged edge
- of a sheet element may be inserted edgewise 45 between the flanges and anchored to the element thereby.
10. In a visible index device, an elongated member having bearing loops intermediate its ends and projecting from one face thereof, a channel-shaped sheet metal element disposed with its bottom wall against the said face of the elongated member, said element at one edge being longer than at the other and the flange of such longer edge being 50 rolled over to provide bearing tongues which are rotatably received in said bearing loops, one of the sides of the channel element having an angular flange extending over and in spaced relation to the other edge of the 55 channel for confining within the channel the flanged edge of an index sheet.
11. In a visible index device, a carrier for index sheets comprising an elongated member adapted to slide in guideways of a supporting frame and having bearing projections upon the upper face thereof, a sheet metal element hinged in said bearing projections and having means for slidably receiving and retaining an edge of an index sheet, 60 whereby the projections will limit sliding of said sheet until the sheet is flexed to clear said projections, the sheet at the edge mounted in said element having a length less than the distance between said bearing projections. 65
12. In a visible index device, an element adapted to slide laterally of itself in guideways of a supporting frame and having means for supporting an index sheet for sliding movement lengthwise of the element, 70 said element having projections normally limiting the sliding movement of said elements. 75
- In witness whereof, I hereunto subscribe 80 my signature.

WILLIAM A. RINGLER.
